ROLLING PIN

Earl S. Tupper, Smithfield, R. I.

Application October 25, 1956, Serial No. 43,526

Term of patent 14 years

(Cl. D44—29)

Fig. 3

Fig. 4

Figure 1 is a view in perspective of a rolling pin embodying my new design;

Figure 2 is a front view in elevation thereof;

Figure 3 is one end view in elevation thereof; and

Figure 4 is the opposite end view in elevation thereof.

I claim:

The ornamental design for a rolling pin, substantially as shown.
